United States Patent Office

Des. 198,923
Patented Aug. 18, 1964

198,923

EXERCISING DEVICE

Duane E. Mitchell, Shandon Rte., Paso Robles, Calif.

Original design application Mar. 19, 1963, Ser. No. 74,035.
Divided and this application Mar. 20, 1964, Ser. No.
79,371

Term of patent 14 years

(Cl. D34—5)

The single figure of the drawing is a perspective view of an exercising device embodying my new design.

The dominant features of my new design are shown in solid lines.

This application is a division of co-pending application D. 74,035, filed March 19, 1963.

I claim:

The ornamental design for an exercising device, substantially as shown and described.
